UNITED STATES PATENT OFFICE.

HOWARD B. SHERMAN, OF BATTLE CREEK, MICHIGAN.

MACHINE FOR DRAWING OR STAMPING METAL.

1,117,097.

Specification of Letters Patent. Patented Nov. 10, 1914.

Application filed March 30, 1914. Serial No. 828,268.

To all whom it may concern:

Be it known that I, HOWARD B. SHERMAN, a citizen of the United States, residing at Battle Creek, in the county of Calhoun and State of Michigan, have invented certain new and useful Improvements in Machines for Drawing or Stamping Metal; and I hereby declare that the following is a full, clear, and exact description thereof, reference being had to the accompanying drawings, which form part of this specification.

This invention is a novel improvement in multi-stage presses or machines for drawing or stamping metal; and its particular object is to enable a plurality of operations to be performed upon a blank without manual handling thereof.

The invention comprises a plurality of operative mechanisms and novel means for automatically carrying the blanks delivered from one mechanism to the next mechanism, to be operated upon thereby before being discharged from the machine.

The machine shown in the drawings has two mechanisms adapted to successively operate upon blanks, and novel means for transferring the objects being worked from one mechanism to the other; and a description of such machine will suffice to explain the essential characteristics of the invention, but the capacity of the machine can be increased by using a larger number of mechanisms in such relation to the blank carrier or transferring devices as will enable an increased number of operations to be performed upon the blank or object in its passage through the machine.

The specific machine shown in said drawings comprises a double-acting draw press and a single acting draw press arranged in the same main frame, and preferably side by side and with the bed of one below the bed of the other; with a transferring device or rotary carrier which receives the blanks after being operated upon by the double action press and transfers them to position to be acted upon by the single acting press. This carrier is preferably arranged to operate beneath the die plate or bed of the double acting press and above the die plate or bed of the single acting press. In the preferred form of the machine this carrier is made annular and surrounds the central column of the machine.

Other novel features of the invention will be hereinafter explained in connection with the detailed description of the machine

illustrated in the said drawings; which will suffice to enable those skilled in the art to utilize the invention; it being understood that the particular construction of the draw presses or operative mechanisms of the machine, are not *per se* essential features of the present invention; the features and combinations of parts for which protection is desired being summarized in the claims.

In said drawings: Figure 1 is a side elevation of a machine embodying the preferred form of the invention. Fig. 2 is a detail transverse sectional view thereof, on the line 2—2, Fig. 1, looking downward. Fig. 3 is an enlarged detail vertical sectional view on line 3—3, Fig. 2.

As illustrated in the drawings, in the main frame of the machine are mounted a double acting draw press, or other operative mechanism, and a single acting draw press, or other operative mechanism, these being arranged side by side. For convenience I will hereinafter refer to these mechanisms as double-press and single press—but such terms are merely illustrative of the invention, and not definitive thereof—and are intended to include any mechanisms with which the novel blank or object transferring mechanism or carrier could be usefully employed.

As shown the single acting press portion of the frame of the machine has a bed 1 and uprights 2 and 2^a which are connected by a top bar 3, and said uprights are provided on their inner faces with guides for a vertically movable cross-head 4 connected by a pitman 4^a with a crank 5^a on a main shaft 5 suitably journaled in the uprights 2, 2^a. The cross head 4 is provided with a drawing tool 4^m of any suitable construction adapted to coöperate with a suitable die 4ⁿ on the bed 1 in the usual manner. The double-press portion has a bed 1^c, preferably standing above the bed 1 and connecting the central member 2^a with an outside upright 2^b; parts 2^a and 2^b, being connected by a top member 3^a. Between the members 2^b and 2^a is a vertically movable cross head 7, which may be operated by means of pitman 7^a connected to cranks or eccentrics 5^c on the shaft 5; and within the cross head is a reciprocating plunger 8 which may be connected by a pitman 8^a with a crank or eccentric 5^f on shaft 5. These parts may be of any desired or preferred well known construction and arrangement and are adapted to reciprocate the cross head 7 and plunger 8 in

such manner that, as usual, the die 7^m attached to cross head 7 will operate before the drawing tool 8^m attached to the plunger 8. The die 7^m first cuts a blank from a sheet of metal interposed between it and a suitable die on the bed 1^c, and then dwells while the plunger 8 works inside and through the cross head 7 and causes the tool 8^m to draw the metal blank through a die 8ⁿ on the bed 1^c in the usual manner.

10 The shaft 5 may be driven by gears 5^b on its end meshing with pinions 6^a on a counter-shaft 6 provided with a belt pulley 6^b, or other means for actuating same. This construction relieves torsional strain on the shaft 5 when in operation.

15 The operative parts thus far described, except for their relative grouping and arrangement, may be of any usual or desired construction.

20 In the preferred form of the invention shown in Figs. 1 to 3 I employ an annular carrier 9 to receive the object or blanks forced through the die 8ⁿ and carry them into position over the die 4ⁿ to be operated upon by the tool 4^m. Said carrier 9 may be made in sections rigidly bolted together as indicated at 9^a, so that it can be readily assembled in position around the lower portion 25 of the standard 2^a; and said carrier may be supported above the bed 1 and below the bed 1^c in any suitable way so that it can be rotated in a horizontal plane, and around the standard 2^a. As shown in Figs. 30 2 and 3 this carrier 9 may be rotatably supported upon a split collar 10 bolted around the lower portion of the standard 2^a, said collar 10 being circular and fitted within a circular flange 9^c on the lower side of the 35 carrier 9 to prevent lateral displacement of said carrier during its rotation; and said carrier may be mounted upon this collar by ball bearings 10^a as indicated in Fig. 3.

40 The carrier may be rotated step by step 45 by any suitable means; in the drawings the flange 9^c is shown as provided with ratchet teeth 9^b on its exterior periphery adapted to be engaged by a reciprocatory ratchet lever 11, which may be yieldingly held in contact 50 with the ratchet teeth 9^b by a suitable spring, as 11^a, and which may be reciprocated by any suitable means. The outer end of lever 11 is connected by a pivotal joint 11^b to one arm of a bell crank lever 12, pivoted at 12^a 55 on a bracket attached to the standard 2^b, and the other arm of this lever is pivotally connected at 12^b to the lower end of a vertical rod 13, the upper end of which may be slotted to pass the shaft 5, and carries a pin 60 5ⁿ engaging a cam 5^m, attached to the shaft 5, so that during each rotation of shaft 5 the rod 11 will be reciprocated and move the carrier 9 one step. This carrier 9 is provided with a series of apertures 9^e which 65 are adapted to successively register with an

opening 8^e in bed 1^c below die 8ⁿ, and with an opening 4^e in bed 1 above die 4ⁿ; and the presses are so operated that after a blank (indicated in dotted line at B) is forced by tool 8^m through the die 8ⁿ it drops into one 70 of the apertures 9^e in the carrier, and is retained therein, and ultimately brought by said carrier into position above the die 4ⁿ, and while in such position the tool 4^m will descend and eject the blank from the carrier and force it through the die 4ⁿ and discharge it through the opening 4^e.

75 In a machine such as shown in Fig. 1, three distinct operations will be automatically performed on each blank passing through the machine; for instance, the die 7^m will cut a blank from the material; the tool 8^m will press said blank through the die 8ⁿ and discharge it into the carrier 9; this carrier will then take the same blank 80 around to die 4ⁿ, where it will be engaged by the tool 4^m and forced through the die 4ⁿ, and discharged through the opening 4^e. By having the carrier operate below one bed and above the other the blanks discharged from the first press are more readily brought into proper position for operation upon the second press.

85 A machine embodying the invention practically has all the capacity of two separate machines and is more economical to construct and operate than two separate machines. The central standard takes the place of two of the side columns of the separate machines; and but one crank shaft is required. The invention further obviates the necessity of employing an attendant operator for the second press. The invention furthermore not only reduces the cost of construction and enhances the speed of production, but lessens the number of operatives required and reduces the liability of accidents to such operatives as no manual handling is required to feed objects to the 90 second mechanism.

100 While I have shown a plurality of presses or mechanisms as arranged side by side, I do not consider the invention restricted to the exact arrangement shown, nor to the specific form of construction herein shown.

105 By this invention I provide a double or plural machine which may have a single action movement on each side, or a double action movement on each side, or a double action movement on one side and a single 110 action on the other; and which has a carrier preferably revolving around the center column or standard, and adapted to receive work from one mechanism and carry it into position to be operated upon by the 115 other mechanism.

120 What I claim is:

1. In combination, a main frame having central and side standards and beds between the said standards, and a carrier in line with 130

the central standard and moving around it adapted to receive objects from one bed and carry same around the central standard to and over the other bed into position to be 5 operated upon, and means for operating said carrier.

2. In combination, a main frame having central and side standards and beds between the said standards, and a carrier arranged 10 below the bed of one press and above the bed of the other in line with the central standard and moving around it and adapted to receive objects from one bed and carry same around the central standard to and 15 over the other bed into position to be operated upon, and means for operating said carrier.

3. In combination, a main frame having central and side standards, and beds and 20 press mechanisms arranged between the said standards; a carrier movable around the central standard and arranged below the bed of one press and above the bed of the other adapted to receive objects operated upon by 25 one press and carry same around the central standard to and over the other bed into position to be operated upon by the other press, and means for operating said carrier.

4. In combination, a main frame having 30 central and side standards, adjacent press mechanisms arranged between the said standards, an annular carrier surrounding the central column adapted to receive the objects operated upon by one press and carry 35 same into position to be operated upon by the other press, and means for operating said carrier.

5. In combination, a main frame having central and side standards and adjacent press 40 mechanisms arranged between the said standards, and an annular carrier arranged below the bed of one press and above the bed of the other and surrounding the central column, said carrier being adapted to receive 45 an object operated upon by one press and carry it over into position to be operated upon by the other press, and means for operating said carrier.

6. In combination, a main frame having 50 central and side standards, beds between the standards, and reciprocating cross heads between the standards above the beds, a carrier movable around the central standard and mounted to rotate below the bed of one 55 press and above the bed of the other press and adapted to carry an object discharged from one bed around the central standard into position to be operated upon on the other bed, and means for rotating this carrier step by step.

7. In combination, a main frame having central and side standards, die supporting 60 beds between the standards, and reciproca-

tory cross heads arranged between the standards above the beds, a carrier movable 65 around the central standard and mounted to rotate below the bed of one press and above the bed of the other press and adapted to carry an object discharged from one press around the central standard into position to 70 be operated upon by the other press, and means for rotating this carrier step by step.

8. A drawing press comprising a main frame having central and side standards, die supporting beds between the standards, and reciprocating cross heads arranged between the standards, an annular carrier mounted to rotate around the central standard below the bed of one press and above the bed of the other press and adapted to carry an object 80 discharged from one press into position to be operated upon by the other press, and means for rotating this carrier step by step.

9. In combination, a main frame having central and side standards, beds between the 85 standards, and reciprocating cross heads between the standards above the beds, a carrier rotating on a vertical axis intermediate the beds and in a plane below one bed and above the other, and adapted as it rotates to 90 carry an object discharged from one bed into position to be operated upon on the other bed, and means for rotating the carrier.

10. In combination, a main frame having central and side standards, and press mechanisms comprising cross-heads and co-operating beds arranged between the said standards; a rotatable carrier arranged to rotate on a vertical axis in line with the central standard and below the bed of one press 100 mechanism and above the bed of the other press mechanism, said carrier being adapted to receive objects discharged from one press mechanism and by its rotation to carry same over into position to be operated upon by the 105 other press mechanism, and means for rotating said carrier.

11. In combination, a main frame having central and side standards, die supporting beds between the standards, and reciprocating cross heads arranged between the standards above the beds, a carrier mounted to rotate on a vertical axis below the bed of one press and above the bed of the other press and adapted to receive an object discharged 115 from one press and carry it around the central standard into position to be operated upon by the other press, and means for rotating said carrier step by step.

In testimony that I claim the foregoing 120 as my own, I affix my signature in presence of two witnesses.

HOWARD B. SHERMAN.
